(57) **CLAIM**

The ornamental design for a video camera, as shown and described.

DESCRIPTION

FIG. 1 is a perspective view of a first embodiment of a video camera showing our new design;

FIG. 2 is a right side elevational view thereof;

FIG. 3 is a perspective view thereof wherein the viewing screen is in a first alternate position;

FIG. 4 is a perspective view thereof wherein the viewing screen is in a second alternate position;

FIG. 5 is a perspective view thereof wherein the viewing screen is in a third alternate position; and,

FIG. 6 is a perspective view thereof wherein the viewing screen is in a fourth alternate position.

FIG. 7 is a perspective view of a second embodiment of a video camera showing our new design;

FIG. 8 is a right side elevational view thereof;

FIG. 9 is a perspective view thereof wherein the viewing screen is in a first alternate position;

FIG. 10 is a perspective view thereof wherein the viewing screen is in a second alternate position;

FIG. 11 is a perspective view thereof wherein the viewing screen is in a third alternate position; and,

FIG. 12 is a perspective view thereof wherein the viewing screen is in a fourth alternate position.

The broken lines depicting portions of a video camera in which the claimed design is embodied form no part of claimed design.
